FOREIGN PATENT DOCUMENTS

WO 2011005242 A1 1/2011

Primary Examiner — Elizabeth J Oswecki

(57) **CLAIM**

The ornamental design for a mail catching device, as shown and described.

DESCRIPTION

FIG. 1 is a front elevational view of a mail catching device showing my new design;

FIG. 2 is a rear elevational view thereof;

FIG. 3 is a top view thereof;

FIG. 4 is a bottom view thereof;

FIG. 5 is a left side elevational view thereof, the right side being a mirror image thereof; and,

FIG. 6 is a perspective view thereof, shown in a used condition attached to a door shown in broken lines. The broken line showing of a door in FIG. 6 represents unclaimed environmental subject matter and forms no part of the claim.

1 Claim, 5 Drawing Sheets(56)
